DESIGN.

E. H. & J. H. ELDRIDGE.

COFFIN PLATE.

13,967.

Patented June 5, 1883.

UNITED STATES PATENT OFFICE.

ELI H. ELDRIDGE AND JOHN H. ELDRIDGE, OF TAUNTON, MASSACHUSETTS.

DESIGN FOR A COFFIN-PLATE.

SPECIFICATION forming part of Design No. 13,967, dated June 5, 1883.

Application filed April 12, 1883. Term of patent 7 years.

To all whom it may concern:

Be it known that we, ELI H. ELDRIDGE and JOHN H. ELDRIDGE, of Taunton, in the county of Bristol and State of Massachusetts, have 5 invented a new and Improved Design for Coffin-Plates; and we do hereby declare the following to be a full, clear, and exact description of the same, reference being had to the accompanying drawing, forming part of this 10 specification, and to the figures and letters of reference marked thereon.

Our invention relates to an improved design for the plates which are placed upon the fronts or other suitable portions of coffins to bear the 15 name of the deceased and accompanying inscriptions. Such coffin-plates have heretofore been made in various shapes, with inscription-surfaces surrounded by plain or ornamental borders, and sometimes without borders.

20 The object of our invention is to give the coffin-plates an ornamental and at the same time a significant character independent of the special inscriptions.

Our invention consists in a design for coffin-25 plates in which the front surface of the plate is divided into two sections, one being blank and plain and the other containing emblematical figures or representations embossed, engraved, or otherwise placed thereon.

30 The accompanying drawing represents a coffin-plate designed according to our improvement.

The letter A designates the plate as a whole. B is its blank section to receive inscriptions, and C is its emblematical section. In the 35 present instance the upper edge of the plate is given a somewhat arched form, and has a scroll-work border, d. The emblematical section is divided from the plain section by a scalloped or undulating bead, e. Within the 40 emblematical section are arranged various figures or groups of figures, as shown at f g h i j k l, having emblematical signification.

What we claim is—

1. The design for coffin-plates herein de- 45 scribed, the same consisting in the front surface, divided into sections, one of which is blank, and the other of which contains emblematical figures or representations, substantially as described and shown.

2. The herein-described design for coffin- 50 plates, consisting of the surface divided into two sections, one of which is plain and blank, and the other of which contains emblematical figures, the upper edge of the plate having a scroll-work border, substantially as described and shown.

ELI H. ELDRIDGE.
JOHN H. ELDRIDGE.
